FIG. 1 is a side elevation of the pencil holder embodying my new design;

FIG. 2 is a top plan view thereof;

FIG. 3 is an end elevation thereof; and

FIG. 4 is a vertical section taken along line 4—4 of FIG. 1.

The dominant features of my design reside in a series of longitudinally extending, vertically spaced grooves on each side of a generally rectangular block and a series of apertures in each side groove, formed by the intersection of the side grooves with a series of longitudinally spaced, laterally elongated holes extending downwardly from the top, thereby providing apertures extending laterally through the block all as shown.

I claim:
